CLAIM

The ornamental design for an alpenstock as shown and described.

DESCRIPTION

FIG. 1 is a front, right and top perspective view of an alpenstock, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof.

FIG. 8 is an enlarged bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 2.

FIG. 12 is an enlarged view of detail 12 in FIG. 2; and,

FIG. 13 is an enlarged view of detail 13 in FIG. 3.

The dashed broken lines depict portions of the alpenstock that form no part of the claimed design.

The dot-dash broken lines in FIGS. 1, 2, 3, 9, 10, 11, 12 and 13 depict the boundaries of the enlargements that form no part of the claimed design.

1 Claim, 13 Drawing Sheets
